MECHANISM FOR PROPELLING BOATS

Conrad Carlson, Brooklyn, N. Y.

Application December 1, 1933, Serial No. 700,476

3 Claims. (Cl. 9—25)

This invention relates to mechanism for propelling boats. It is particularly concerned with an improved form of rowing mechanism, and the principal object of the invention is to provide a form of mechanism which permits the rower of the boat to face forward in propelling the boat. It is a further object of the invention to provide a mechanism of the above character which shall be simple, rugged and inexpensive in construction, and which may be applied to the standard types of row boats, by means of a simple clamping mechanism.

Various other features and objects of the invention will appear from the following description of certain preferred embodiments thereof having reference to the accompanying drawings, in which:

Figure 1 is a plan view of a boat with one form of my mechanism applied thereto;

Figure 2 is a detail view, being a section of Figure 1 along lines 2—2 looking in the direction of the arrows;

Figure 3 is a detail view, being a section of Figure 1 along lines 3—3;

Figure 4 is a plan view similar to Figure 1, showing the mechanism of the present invention in folded or inoperative position;

Figures 5 and 6 are detail views showing portions of the mechanism in elevation;

Figure 7 is a plan view of a modification of the mechanism shown in Figure 1, and

Figure 8 is a detail view showing in elevation a portion of the mechanism of Figure 7.

Similar characters of reference designate similar parts in each of the several views.

In Figure 1, reference character 1 designates a row boat of conventional type. Numerals 2 designate oars for propelling the boat. The mechanisms for operating the oars have mirror symmetry with reference to each other and the present description, therefore, will have reference to the mechanism provided on one side, i. e., the port side of the boat, it being understood that the description will apply in similar manner to the mechanism on the starboard side.

The end of oar 2 is received in a clamp 3 provided with a bolt 4, which cooperates with the flange 3^a and 3^b of the clamp for the purpose of holding the end of the oar firmly within the clamp. Clamp 3 is pivotally mounted on a set screw 5 which cooperates with a collar 6 slidable on a sleeve 7 free to turn about a shaft 8. Clamps 11 and 12 are provided for detachably mounting shaft 8 on the side wall of the boat. These clamps are of simple construction and consist of

jaws 10 and 13 for engaging opposite sides of the wall of the boat, as shown in Figures 2 and 3. The shank of jaw 13 is slidable in an opening 14 of jaw 10, and wing nut 15 is provided to secure the clamp in position. Each clamp is provided with a hole 9 to receive the end of shaft 8, and a set screw 16 is provided to secure the shaft firmly in the clamp.

An operating lever 17 is pivotally secured to sleeve 7 by means of parts 17^a, which are similar to clamp 3 and its associated elements for connecting the oar 2 to sleeve 7. A link 18 is provided to connect lever 17 with oar 2, the parts of this connection comprising at each end a clamp 19 similar to clamp 3. Link 18 is bent 15 adjacent each end through a right angle and passed through a hole 20 in each clamp. The ends of link 18 are upset to provide heads 21 to hold the link in position.

The operation of the device of my invention 20 will now be readily understood. The operator of the rowing mechanism is seated on a seat 22 of the boat and faces toward the bow. He then grasps the ends of the levers 17 and operates these like conventional oars. As he pulls the 25 levers toward himself the oars 2 are caused to swing through arcs in a rearward direction. The boat is then propelled in the direction in which the rower is seated. It will be observed that when the ends of lever 17 are depressed, for the 30 return stroke, sleeve 7 will be turned slightly on shaft 8. This rotation is transmitted to the pivots 5 of oars 2, so that the ends of these oars are lifted out of the water, as in conventional 35 rowing practice.

Depending upon the curvature of the side of the boat, clamp blocks 23 are preferably provided in one of the clamps 11 and 12 on each side of the boat, for the purpose of providing such inclination to shaft 8 and sleeve 7 that the position of oar 2 40 will be as shown on the starboard side of the boat of Figure 4, when lever 17 is turned to its extreme rearward position. In this position, it will be observed, the mechanism is folded up and only the tip of oar 2 projects from the periphery of the 45 boat. If desired, the folded mechanism may be turned about shaft 9 into the position indicated at the port side of Figure 4, in which position the blade of the oar is horizontal and substantially the entire oar is within the confines of the boat.

It will be observed that the entire mechanism in its collapsed position may readily be removed from the boat by operating the wing nuts 15 to release the pressure of the clamps 11 and 12.

In the modified form shown in Figure 7, the gen- 55

- eral arrangement is the same as that in the previous form of embodiment, but the parts are so proportioned that instead of the stub oars 2 of Figure 1, full length oars 24 may be employed. 5
5 With this arrangement it is possible for two persons to operate the one set of oars. One of these, who is seated facing forwardly, as on seat 25, will operate the levers 17 and the other, who is seated facing rearwardly as on seat 26, will operate the 10 oars 24 in conventional manner.

Figure 8 illustrates a modification of the mechanism for mounting the oars. In this modification the hollow shaft 8^a which corresponds to shaft 8 of the previous embodiment, is mounted to rotate 15 in the openings 9 of clamps 11 and 12, screw caps 27 being provided to prevent sliding movement of the shaft. The levers 17 and oars 2 are pivotally attached directly to shaft 8^a, the mechanism for effecting this attachment being similar to that 20 shown in Figure 6 and bearing similar reference characters. It will be observed that the latter modified arrangement is even simpler than that of the previous form.

I have described what I believe to be the best 25 embodiments of my invention. I do not wish, however, to be confined to the embodiments shown, but what I desire to cover by Letters Patent is set forth in the appended claims.

I claim:

- 30 1. In combination, an oar, a lever, a shaft, means for detachably mounting said shaft in a substantially horizontal direction on the side wall of the boat, said shaft being free to turn about its axis, means for said lever and said oar for pivotally connecting each of them with said shaft, said means for each comprising a member having an axis at right angles to that of the shaft, about which axis said lever and said oar, respectively, are free to swing, and a link for connecting a 35 point of the lever on one side of its pivot with a 40 point of the oar on the opposite side of its pivot,

said oar having a handle portion extending beyond the point of pivotal connection of the oar to the shaft, to permit operation of said oar by force applied to said handle portion.

2. In combination, an oar, a lever, a shaft, 5 means for detachably mounting said shaft in a substantially horizontal direction on the side wall of the boat, said shaft being free to turn about its axis, means for said lever and said oar for pivotally connecting each of them with said shaft, said 10 means for each comprising a member having an axis at right angles to that of the shaft, about which axis said lever and said oar, respectively, are free to swing, and means for each member for permitting adjustment of the position of said 15 member longitudinally of said shaft, and a link for connecting a point of the lever on one side of its pivot with a point of the oar on the opposite side of its pivot, said oar having a handle portion extending beyond the point of pivotal connection 20 of the oar to the shaft, to permit operation of said oar by force applied to said handle portion.

3. In combination, an oar, a lever, a shaft, 25 means for detachably mounting said shaft in a substantially horizontal direction on the side wall of the boat, said shaft being free to turn about its axis, means for said lever and said oar for pivotally connecting each of them with said shaft, said 30 means for each comprising a member having an axis at right angles to that of the shaft, about which axis said lever and said oar, respectively, are free to swing, and means for each member for permitting adjustment of the position of said 35 member longitudinally of said shaft, a slideable clamp on the lever on one side of its pivot, another slideable clamp on the oar on the other side of its pivot, and a link connecting said clamp, said 40 instrumentalities affording in combination a means to secure virtually universal adjustments between said oar and its operating lever.

CONRAD CARLSON.
